Claims priority, application Germany April 15, 1953

7 Claims. (Cl. 260—413)

This invention relates to improvements in the working up of distillation fractions containing alcohols and hydrocarbons.

Higher alcohols may be produced by catalytically adding carbon monoxide and hydrogen to mixtures of olefins, such as isomeric and/or homologue mixtures. The catalytic addition may be effected in the absence or presence of saturated hydrocarbons. As a result of the catalytic addition, the next higher alcohols are produced. The olefins in the mixture may be isomeric with respect to the position of the double bond and/or if alkyl side chains are present, with respect to these side chains. The alcohol mixtures obtained in this manner must be separated by distillation for further commercial use. This may result in fractions in which branch-chained alcohols and hydrocarbons distil over in the same boiling range, and for this reason cannot be separated by distillation. These fractions, which hereinafter will be referred to in both the specification and claims as intermediate fractions could not be utilized in an advantageous manner up to the present.

The intermediate fractions obtained could be charged to a subsequent distillation. This, however, would merely result in a continuous increase of the intermediate fraction. Prior to the present invention, these intermediate fractions could neither be utilized as hydrocarbon products due to their high content of alcohols and could not be utilized as alcohol products due to their high hydrocarbon content.

In addition to these alcohol hydrocarbon distillation fractions obtained in the processing of raw alcohols obtained from olefins of the Fischer-Tropsch synthesis, other similar hydrocarbon alcohol-containing fractions are obtained from other starting materials. A similar type of intermediate fraction is obtained from the fractionation of crude alcohols obtained from olefins which have been formed by the chlorination and dechlorination of paraffins. In the treatment of polymerized olefins produced from liquid or gaseous unsaturated petroleum hydrocarbons, similar fractions may also be obtained.

One object of this invention is a process for working up such intermediate fractions which contain alcohols and hydrocarbons to produce branch-chain fatty acids. This, and still further objects will become apparent from the following description:

It has now been found that fractions containing alcohols and hydrocarbons, such as the intermediate fractions described above, may be processed in an advantageous manner with the formation of valuable branch-chain fatty acid by the treatment of such a fraction with caustic alkali in amount substantially corresponding to the hydroxyl number of the intermediate fraction or slightly in excess there-

2

of at temperatures of 250–350° C. at increased pressure; thereafter distilling off the hydrocarbons present at any desired pressure, injecting water into the agitated melt under increased pressure, removing the water-containing pasty soaps thus formed at a temperature not in excess of 200° C. from the reaction vessel, and decomposing these soaps in the known manner with mineral acids after dissolution in water with the addition, if desired, of water-soluble alcohols and after extraction with water-insoluble salts.

10 The boiling range of the aforementioned intermediate fractions at normal atmospheric pressure (760 mm. Hg) is approximately as follows, depending on the molecular size:

	° C.
C ₁₂	205–245
C ₁₃	240–275
C ₁₄	260–290
C ₁₅	280–305
20 C ₁₆	295–320

For carbon monoxide hydrogenation products produced by means of iron catalysts and with a production of 5,500 kilograms of alcohol, there are obtained approximately 25 1,000 kilograms of intermediate fractions to be processed in accordance with the invention and 15,000 kilograms of first runnings which substantially consist of paraffinic hydrocarbons.

The branched-chain fatty acids obtainable in this manner are suited for various commercial uses. They may, for example, be processed to give low pour point ester oils. It is also possible to obtain textile auxiliary agents, cold-resistant plasticizers, and mineral oil additives therefrom. The process of the invention thus makes possible 35 the economical conversion into valuable finished products of intermediate fractions which have hitherto been treated as waste products.

The process is preferably carried out in such a manner as to subject the intermediate fractions to be processed 40 to a treatment with alkali at 250–350° C. and super-atmospheric pressure and thereafter to effect the then possible separation by distillation into hydrocarbons and oxygenated products.

The treatment with caustic alkali should be effected 45 with an amount of alkali corresponding to the hydroxyl number of the mixture treated. The amount of caustic alkali should preferably not be in excess of 110% of the theoretically required quantity based on this hydroxyl number. Besides sodium hydroxide, the alkali treatment

50 may also be effected with potassium hydroxide. Based on the hydroxyl number present, quantities of alkali which, if desired, are far in excess of 10% of the stoichiometrically required quantity may be used in this case. For economic reasons, however, not more caustic alkali

55 is used than is required for the conversion of the alcohols into carboxylic salts. The quantity which should preferably be used is generally about 110% of the theoretically required quantity. The alkali treatment may be effected at atmospheric pressure of more than 10 kg.

60 per square centimeter and preferably more than 50 kg. per square centimeter. The gas pressures developing during the alkali treatment are dependent on the volatility of the hydrocarbons involved. If highly branched carboxylic acids having 12 and more carbon atoms in the molecule are produced, then the gas pressures will rise not higher than to 10–100 kg. per square centimeter.

The hydrogen split off during the alkali treatment should preferably be continuously removed, so that the pressure formed does not exceed more than 50 kg. per sq. cm. The hydrogen split off is thus preferably continuously removed at pressures in excess of 50 kg. per square centimeter. After the termination of the hydrogen evolution, the pressure is released and preferably released to atmospheric pressure, while substantially maintaining the melting temperature. This will cause the hydrocarbons to distil off. In the case of hydrocarbons having a molecular size of more than C₁₀, reduced pressure may be required for the distillation. In any case, as soon as the distillation of the hydrocarbons ceases, it is preferable to continue the distillation by reducing the pressure and maintaining the melting temperature, so that practically all the hydrocarbons can be removed, thus eliminating the necessity of a later extraction of the soap solution for the purpose of removing the unsaponifiable portions.

After the removal of the hydrocarbons by distillation, water is injected into the reaction vessel preferably with stirring. The amount of water injected may be between 10 and 50%, preferably 30% of the melt treated. The paste formed after the injection of the water is removed from the reaction vessel at temperatures not in excess of 200° C. The removal from the reaction vessel, as, for example, the pressure vessel, is effected by forcing the paste from the vessel by an internally applied pressure or externally applied partial vacuum. The soap paste, while stirring, is allowed to flow into a quantity of water which is preferably 2 to 4 times that of the soap paste.

The process may, for example, be carried out as follows:

The mixture required of alkali and intermediate fraction is placed into a pressure-resistant melting vessel which is suitably lined with copper. The pressure vessel is then closed, purged with nitrogen, and heated while constantly stirring with the initial nitrogen pressure being 1 to 2 kg. per square centimeter. Depending upon the partial pressure of the hydrocarbons present, the reaction pressure increases and is additionally increased by the splitting-off of hydrogen commencing at about 250° C. After a pressure of about 50 kg. per square centimeter is reached, sufficient hydrogen is allowed to blow off through a pressure relief valve as to maintain said pressure of 50 kg. per square centimeter.

The reaction is now allowed to proceed to completion, while increasing the temperature to about 320° C. and thereafter the hydrogen is removed by completely releasing the pressure. Depending upon the boiling range of the hydrocarbons subjected to the treatment with alkali, the prevailing pressure will be sufficient to cause a distillation of the hydrocarbons. With hydrocarbons of the molecular size C₁₄, a distillation of this kind will take place under a pressure of as low as about 6 kg. per square centimeter. As soon as this distillation of hydrocarbons ceases, the distillation is continued by reducing the pressure while maintaining the melting temperature. In this manner, practically all of the hydrocarbons can be removed from the soap, thereby eliminating the necessity of a later extraction of the soap solution for the purpose of removing unsaponifiable portions, as is required for the production of commercially pure fatty acid products.

After the complete removal of the hydrocarbons, water is injected into the pressure vessel, while the stirring is continued, and while the melt is still in the hot liquid state. Prior to that, the hydrogen formed is advantageously completely removed. In this case, approximately atmospheric pressures may be used in introducing the water. If the water is to be injected to the melt prior to the complete removal of the hydrogen, a pressure must be used which is in excess of the prevailing hydrogen pressure. In this case, the pressures to be used range

up to 50 kg. per square centimeter. The reaction vessel in this case must be sufficiently resistant to the increase in pressure taking place by the partial pressure of water vapor. The temperature of the melt ranges at about 200-250° C. The water to be injected may be at temperatures of approximately 10-80° C. Less than 50% of water, based on the weight of the melt, will generally be injected. Larger quantities may be used if the capacity of the reaction vessel is large enough. By the injection of water, the anhydrous soap, which is very hard after solidification, is converted into a soft-water-containing pasty mass. This paste is particularly well suited for processing because the soap material in this state can be forced or pumped out of the reaction vessel at temperatures not in excess of 200° C. Moreover, the dissolution of this soap paste in water required for precipitating the branched fatty acids by means of acids can be effected in the pasty state without any difficulty, while the dissolution of an anhydrous soap, even after thorough comminution, requires a long time.

The decomposition of the resulting soap by mineral acids for the purpose of recovering free fatty acids is effected by known processes. The fatty acids may completely be set free by mineral acids. It is possible, however, if desired, to separate at first an acid soap by means of carbon dioxide, thereby saving a part of the mineral acid required. The decomposition of the soaps obtained by the alkali treatment may, for example, be effected with sulfuric, hydrochloric, nitric, carbonic, formic, acetic or oxalic acids. The mineral acids are preferably used in the form of 10-20% solutions. If carbon dioxide is to be used, the pressure applied must be not less than 1-2 kg./square centimeter. The decomposition of the soaps may be effected at normal room temperature or at temperatures of as high as about 90° C. In any case, the reaction mixture must thoroughly be stirred in decomposing the soaps.

The branched fatty acid obtained by the process of the invention can be freed from coloring matter by distillation. To obtain chemically pure fatty acids, the aqueous soap solution may, if desired after admixture of water-soluble alcohols, be treated with hydrocarbons, thereby removing small portions of unsaponifiable constituents still present. If desired, a fractional separation by molecular sizes may be obtained by using suitable extracting agents (see German Patent No. 868,951). Moreover, it is possible, by partial precipitation by means of mineral acids, to remove small amounts of straight-chain fatty acids which are present in the mixture of branch-chain fatty acids obtained in accordance with the invention. This is achieved with an incomplete saponification which, if necessary or desired, is repeated several times with the quantities of alkali used being kept sufficiently low that no noteworthy separation by molecular sizes occurs.

The process of the invention is particularly advantageous for the processing of raw alcohols obtained from olefins of the Fischer-Tropsch synthesis. It is, however, also applicable to alcohol mixtures obtained from other starting materials. It is, in addition, well suited for the treatment of intermediate fractions of crude alcohols obtained from olefins, which, in turn, are formed by chlorination and dehydrochlorination of paraffins. Crude alcohol mixtures from polymerized olefins produced from liquid or gaseous unsaturated petroleum hydrocarbons may also be processed in accordance with the invention.

The water-soluble alcohols used may be low-cost low molecular weight alcohols, e. g. commercial methyl alcohol (methanol), denatured ethyl alcohol or isopropyl alcohol. Suitable solvents are saturated aromatic and hydroaromatic hydrocarbons boiling between 50° and 250° C.

Further details will become apparent from the following examples, which are given by way of illustration and not limitation:

5

Example 1

600 grams of a hydrocarbon-alcohol mixture obtained in the recovery by distillation of a C₁₅ alcohol, which had been formed by the catalytic addition of water gas to an olefin-containing hydrocarbon mixture from catalytic carbon monoxide hydrogenation having the molecular size C₁₄, were placed into a pressure vessel of 2900 cc. capacity provided with a copper insert and a copper stirrer. This hydrocarbon-alcohol mixture had the following characteristics:

Density at 20° C.	0.801
Refractive index, n_D^{20}	1.4391
Neutralization number	0.4
Saponification number	4.6
Hydroxyl number	110
Iodine number	2
Carbonyl number	3
Pour point	°C. -4

To this product there were added 52.2 grams caustic soda (NaOH), corresponding to 110% of the hydroxyl number of the mixture. Thereafter, the pressure vessel was closed, purged two times with nitrogen, and then a nitrogen at a pressure of 2 kg. per square centimeter was passed into the gas space of the pressure vessel. Following this, the stirrer was started and the pressure vessel was heated. At 320° C. a pressure of 50 kg. per square centimeter was reached. This pressure was not allowed to increase beyond 50 kg. per square centimeter by opening a needle valve on the vessel. In this manner, 11 normal liters of hydrogen were removed from the pressure vessel. When, at 320° C. the pressure no longer increased, all of the hydrogen was withdrawn, while maintaining the temperature. The hydrogen withdrawn, after being released from pressure, corresponded to a gas quantity of 55 normal liters.

At a reaction pressure of as low as 6 kg. per square centimeter, hydrocarbons distilled from the pressure vessel, and were condensed by a cooler and separated from the gaseous products. After atmospheric pressure was reached, a vacuum of about 10 mm. Hg was applied, whereby the remainder of the hydrocarbons distilled off from the reaction product contained in the pressure vessel. This resulted in 308 grams oily constituents corresponding to 51.4% of the material charged. Based on the characteristics given above, a content of neutral oil of 52% was theoretically to be expected.

150 cc. of water were then injected by means of nitrogen into the pressure vessel, which had meanwhile cooled to 250° C., while continuing the stirring for about 10 minutes. The soap paste formed was then removed from the pressure vessel by means of a discharge pipe which extended down to the bottom of the pressure vessel. The paste was dissolved in 1500 cc. of water while stirring, and mixed with about 650 cc. 20% sulfuric acid, thereby adjusting the pH value to 5 and resulting in the separation of a C₁₅ fatty acid mixture at the surface. The mixture was washed two times with hot water, whereafter about 300 grams of a finished product remained, which had the following characteristics:

Neutralization number	227
Saponification number	231
Pour point	°C. -7

The neutral oil distilled off had the following characteristics:

Density at 20° C.	0.767
Refractive index n_D^{20}	1.4300
Hydroxyl number	2
Neutralization number	0
Saponification number	0.3

6

Example 2

600 grams of an intermediate fraction which had been obtained in the distillation of a C₁₅ alcohol were charged to the pressure-resistant melting vessel used in Example 1. The alcohol had been produced from chlorinated and dehydrochlorinated paraffins of the molecular size C₁₄ by the catalytic addition of water gas and subsequent hydrogenation. The intermediate fraction had the following characteristics:

Density at 20° C.	0.804
Neutralization number	0.2
Saponification number	1.4
Hydroxyl number	104
Iodine number	2
Carbonyl number	12
Refractive index, n_D^{20}	1.4402
Pour point	°C. -6

20 This product was mixed with 50 grams NaOH and the mixture was further processed in accordance with Example 1. This resulted in 315 grams C₁₄ hydrocarbons having the following characteristics:

Density at 20° C.	0.766
Refractive index, n_D^{20}	1.4285
Neutralization number	0
Hydroxyl number	1

25 The treatment of the aqueous soap solution with acid resulted in about 290 grams of a C₁₅ fatty acid mixture having the following characteristics:

Neutralization number	224
Saponification number	231
Hydroxyl number	0
Iodine number	0
Carbonyl number	0
Density at 20° C.	0.883
Refractive index, n_D^{20}	1.4465
Pour point	°C. -45

We claim:

45 1. Process for the treatment of an intermediate fraction of alcohols and hydrocarbons obtained in the processing of higher alcohol mixtures produced from olefin mixtures in accordance with the oxo-synthesis which comprises contacting such an intermediate fraction with

50 an amount of caustic alkali at least substantially corresponding to the hydroxyl number of the intermediate fraction contacting being effected at a temperature of about 250-350° C. and at an increased pressure, distilling off hydrocarbons from the melt formed by the alkali reaction, said distillation being at least partially effected at a reduced pressure, thereafter mixing an amount of water with the melt formed sufficient to form a pasty soap, decomposing the soap with a mineral acid and recovering the fatty acid produced.

55 2. Process in accordance with claim 1, in which said contacting with caustic alkali and mixing with water is effected in a pressure vessel, and in which after the formation of the pasty soap the same is removed from the pressure vessel at a temperature not in excess of about 200° C.

60 3. Process in accordance with claim 1, in which said contacting is effected with an amount of caustic alkali not substantially in excess of 110% of the theoretically required quantity.

65 4. Process in accordance with claim 1, in which said contacting with caustic alkali is effected at a pressure of more than 10 kg. per square centimeter.

70 5. Process in accordance with claim 4, in which said contacting is effected at about 50 kg. per square centimeter and the hydrogen split off during said contacting

is continuously removed at a pressure in excess of 50 kg. per square centimeter.

6. Process in accordance with claim 1 in which, after the termination of hydrogen evolution caused by said contacting with caustic alkali, the pressure is released to 5 atmospheric pressure.

7. Process in accordance with claim 1 in which said mixing with water is effected with an amount of water of about 10-50% of the melt treated.
